TWISTER HEAD ELECTRIC STOP

Elmer G. Steuber, Pittsburg, Calif., assignor to
Columbia Steel Company, a corporation of
Delaware

Application February 29, 1944, Serial No. 524,505

3 Claims. (Cl. 57—81)

The present invention relates to an electric stop mechanism incorporated in the twister head of a stranding or rope-laying machine. It is broadly old to provide means for stopping stranding machines automatically upon the breakage of strand wire, but the machines of the prior art have inherent features of design which prevent their effective use in restricted space. The present invention overcomes the disadvantages of the prior art and provides an arrangement whereby breakage of wire can be detected at a point very close to the twisting point.

The invention will be fully apparent from the following detailed disclosure and the appended claims when read in connection with the accompanying drawings.

In the drawings:

Figure 1 is an elevation of a stranding or rope-laying machine embodying the present invention.

Figure 1^a is an elevation of tensioning means for pulling the cable or rope-like structure passing through the strand closing die of the machine shown in Figure 1.

Figure 2 is an enlarged vertical longitudinal section through the twister head.

Figure 3 is a section on line III—III of Figure 2, at a reduced scale.

Figure 4 is a section on line IV—IV of Figure 3.

Figures 5 and 6 are sections on correspondingly numbered lines of Figure 2.

Referring in detail to the drawings, 10 represents the base of a stranding or rope-laying machine. Supported on the base are a plurality of standards 12 carrying rollers 14 which support a flier 16 for rotation about a substantially horizontal axis. The flier rotatably supports a plurality of spools 18 in a conventional manner, for supplying wire or similar strand material 20. In the embodiment of the invention illustrated, there are seven spools 18, six of which supply wire or like strand material for outer strands of a rope or cable, and the seventh supplies a center core strand 20^a. The strand material passes through suitable guides 22 in the flier, and around suitable guide sheaves 24. The outer strands from the six spools pass over sheaves 26 at the end of the flier, and thence converge through outer guide bushings 28 which are mounted for free movement in guide slots 30 formed in a member 32 constituting part of the twister head. Normally the strands 20 hold the guide bushings 28 inwardly against the action of centrifugal force which naturally tends to move said guide bushings 28 outwardly.

The central core strand 20^a passes through a

guide member 28^a which is mounted with freedom for movement relative to the member 32 in a guide slot 34 formed in the member 32. The several guide bushings 28 and 28^a normally occupy the positions of Figures 5 and 6. A guide plate 36 secured by bolts 37 serves to movably retain the several guides 28 and 28^a within their guide slots formed in the member 32 which constitutes the main body portion of the twister head. The several strands 20 converge from the guide bushing 28 to a closing die 38. The rotation of the flier twists the strands together in a conventional manner so that beyond the closing die 38 a rope or cable-like structure is formed. Tension is maintained on the strands in the usual manner, by passing the rope or cable several times around capstans 40 and 42 mounted on suitable standards 44 and 46 and driven by any suitable conventional means. The completed cable, as indicated at 48, is led off to a suitable take-up drum (not shown).

The several guide bushings 28—28^a serve the double function of guiding the strands and actuating an electrical stop mechanism. These guide members 28 and 28^a are loosely positioned or mounted in the twister head. Such loose mounting is of importance because it permits the guides to turn relatively to the twister head, and thus prevents grooving and distributes the wear. When any given strand 20 or 20^a breaks or develops an undue amount of slack, centrifugal force causes the bushings 28 or 28^a to move outwardly. When the bushings 28 move outwardly, they are adapted to make contact with a ring 50 which surrounds the member 36 and which is insulated from said member and from the frame of the flier. The ring 50 carries two inwardly-extending arms 52 and 54. A terminal bolt 56 passes through the arm 52 and engages an insulating bushing 58 secured to the twister head member 32. A suitable terminal bolt 60 passes through the arm 64 and engages an insulating bushing 62 likewise secured to the member 32 of the twister head. Conductor wires 66 electrically connect the terminals 56 and 60 and therefore the ring 50 with a collector ring 68 which, as shown in Figure 1, is insulated from the flier but rotates therewith. Coacting with the collector ring 68 is a brush 70 which is connected by wire 72 with a solenoid 74 or equivalent electromagnetic element which is in turn connected by wiring 76 with the secondary winding 78 of a transformer 80. The secondary winding 78 is connected by a wire 82 which is grounded at 84 to the flier.

Line wires L^1 , L^2 and L^3 supply 3-phase, 440-volt alternating current at 60 cycles, for powering the motor 86 which is connected through suitable reduction gearing 88 and coupling 90 with the flier. The primary winding 92 for exciting the secondary 78 of the transformer 80 is connected across the lines L^1 and L^2 , as shown.

The solenoid or equivalent element 74 is effective to actuate the movable switch member 94 of a conventional form of motor control relay, so as to open the circuit across the contacts 96 automatically, whenever a strand wire 20 or 20^a breaks. The motor control circuit includes a conventional normally closed stop push button 98 and a conventional normally open start push button mechanism 100. In normal operation the tension on the strand wires 20 and 20^a holds the several guide bushings 28 and 28^a substantially in the position of Figure 5 or Figure 6. So long as the strand guides are held in this position, the control circuit through the electromagnetic element 74 is open, and thus the motor control switch 94 maintains a closed motor circuit across the contacts 96. Upon breakage of any one of the outer strand wires 20 or the inner core strand wire 20^a, the guide bushings 28 or 28^a, being no longer restrained by strand tension, will fly outwardly under the influence of centrifugal force, thus closing the control circuit through the electromagnetic element 74, thereby opening the switch 94, breaking the motor control circuit across contacts 96 so as to automatically stop the motor and prevent the damaged wire from being laid up into the completed cable.

The normally open push button station 160, when closed momentarily, completes the control circuit L^3 energizing the magnet coil M. The magnet coil M pulls the motor contactors M^1 together, completing motor circuit to energize the motor 86. At the same time the auxiliary contact M^2 for the control circuit is closed, thereby maintaining motor control circuit closed until opened by either the normally closed contactor 96 or the stop button station 98.

The motor 86 may be assumed to drive the capstans 40 and 42; or, if desired, these capstans can be driven by an individual motor whose circuit will be opened upon the opening movement of the switch 94.

While I have described quite precisely an embodiment of the invention which a reduction to practice has shown to be highly desirable, it is to be understood that various modifications may be made within the scope of the appended claims.

I claim:

1. A stranding or rope-laying machine comprising, in combination, a flier, an electric motor for driving said flier, an electric power circuit for said motor, a switch controlling the operation of said motor, spools mounted by said flier for supplying strand material, means for pulling the strand material from said spools, a twister head

carried by the flier and having movably mounted thereon a plurality of respective guide members through which the strand materials pass while en route to said pulling means, electromagnetic means capable of operating said motor control switch, an electric control circuit for said electromagnetic means passing through said flier, and a contact ring carried by the twister head and insulated therefrom and from the flier, said control circuit being normally open between said ring and said flier, the parts being so constructed and arranged that upon breakage of any strand of said material the guide member through which it passed will be thrown outwardly by centrifugal force, thus closing the control circuit and energizing said electromagnetic means, which in turn will open the motor control switch and thus stop the machine.

2. A stranding machine of the character described, comprising a rotatably mounted flier carrying a plurality of spools supporting supplies of strand material, a twister head secured to and turning with the flier, strand guides mounted on the twister head with provision for outward movement relative thereto under the influence of centrifugal force, the strand material passing through said strand guides en route to said pulling means, the tension on the strand material normally preventing the outward movement of said guides, a motor for rotating said flier, a switch controlling the operation of said motor, a normally open control circuit including an electrically powered element for actuating said motor control switch, the flier and twister head being included in said control circuit, and a terminal member in said control circuit insulated from the twister head and the flier, any of said guide members being capable of closing the control circuit through said terminal member upon breakage of stranding material, whereby the said element is energized to open said motor control switch and thus stop the machine.

3. A stranding or rope-laying machine comprising a rotary flier carrying a twister head formed with a plurality of radial guide slots, a plurality of strand guide bushings slidable in said slots, a member insulated from the flier and surrounding the bushings, a collector ring rotating with the flier and electrically connected with said member, a control circuit connected on one side with said collector ring and grounded on the other side to said flier, an electromagnetic element in said circuit, and a motor for driving said flier, the circuit of said motor being under control of said electromagnetic element, any of the several guide bushings being adapted to close said control circuit upon breakage of strand wires passing therethrough, said strand wires normally holding said guide bushings in position to maintain the control circuit in open condition.

ELMER G. STEUBER.
